UNITED STATES PATENT OFFICE.

ARTHUR S. GREENE, OF NORTH MILWAUKEE, WISCONSIN.

CONCRETE-MOLD.

1,374,199.

Specification of Letters Patent. Patented Apr. 12, 1921.

Application filed January 14, 1920. Serial No. 351,327.

To all whom it may concern:

Be it known that I, ARTHUR S. GREENE, a citizen of the United States, residing at North Milwaukee, county of Milwaukee and State of Wisconsin, have invented new and useful Improvements in Concrete-Molds, of which the following is a specification.

My invention relates to molds which are used in forming concrete walls.

10 This invention is an improvement upon my earlier invention disclosed in Patent No. 1324811 of Dec. 16, 1919.

Objects of this invention are to provide a concrete mold which may be used to construct a wall and may be moved to successively advanced positions along such walls; which may be adjusted to provide for a corner in such wall; which may be adjusted to provide a continuous hollow space in the wall 20 where a right angle corner occurs; and to provide an improved means for allowing such molds to be readily disengaged from the wall.

Other objects are to provide an adjustable mold which may also be readily and quickly disengaged from the work; to provide an expandible end gate for said mold which will fit and close one end of said mold in all positions of adjustment, and which may readily be removed from the mold and from the work; and to provide an expandible removable auxiliary core for producing a continuous space within the wall when corners are formed.

35 In the drawings:

Figure 1 is a perspective view of the mold adjusted so as to form a corner portion of a wall.

Fig. 2 is a transverse sectional view 40 through one of the adjustable members and through the auxiliary core block.

Fig. 3 is a perspective view of the auxiliary core block.

Fig. 4 is a perspective view of a removable 45 end gate.

The mold comprises side walls 1 and 2 which are reinforced along their upper and lower edges by angle irons 3 and 4 respectively, such angle irons being joined at intermediate portions by vertical bracing angle irons 5.

Vertical bars 6 and 7 extend downwardly through the angle irons 3 and 4 of the respective side walls 1 and 2 and through additional reinforcing plates 8 secured upon these angle irons. These bars or rods 6 and 7 may be secured in any desired manner to the

angle irons as, for example, by means of pins 9 in the lower portion thereof which prevent the withdrawal of the rods. 60

The distance between the walls 1 and 2 may be adjusted by means of the telescoping tubes 10 and 11 which are adapted to be locked in any desired position of adjustment by means of a set screw 12. These tubes are 65 provided with an opening 13 in their lower portion which snugly fits the rods 6 and 7, and forms a pivoted connection therewith, and with an elongated opening 14 in its upper portion which allows lateral motion of 70 the rods at the upper portion of these tubes. These tubes may be finished by providing caps 15 which are threaded upon the ends of the tubes. The upper portions of the rods 6 and 7 are bent toward each other and are 75 threaded in opposite directions as shown at 16, such threads being preferably coarse. The threaded portions are adapted to be loosely engaged by the hubs 17 of a turnbuckle 18 so that such end portions may be 80 drawn toward each other or forced away from each other, to either adjust the horizontal width of the mold or to aid in releasing the mold from the concrete wall in a manner to be described later. Upon the tube 10 is 85 slidably mounted a strap member 19 which is adapted to be clamped in position by means of the screws 20. This strap holds a central core member 21 in adjusted position between the side walls 1 and 2 and allows the mold to 90 be used for making hollow concrete walls. The core is tapered downwardly to facilitate the withdrawing of the mold.

When it is desired to form a corner portion of a wall, an auxiliary core 22, Fig. 3, is 95 positioned between one side wall and the core by hooking the prongs 23, carried by such auxiliary core, into slots 24 and 25 formed respectively in the central core wall and in the outer wall. This auxiliary core is formed 100 of two telescopic members which form a hollow box. A spring 26 is positioned within this auxiliary core and is located adjacent its lower portion for causing such lower portion to press against the walls of the central core 105 21 and outer wall 1.

An end member, or gate, 27 is detachably and pivotally connected by means of bolts 28 which pass through holes in the upper portion of the side walls 1 and 2 and through 110 any one of a plurality of spaced holes 29 formed adjacent the upper side edge of the end member 27. The end gate 27 is telescopic, that is to say, it is formed of two

component parts, each of which comprises a side portion and an end portion, the end portions overlapping. To secure the lower portion of this member 27 in position, latches 30 5 pivoted at 31 to the side walls 1 and 2, are employed. These catches are provided along their lower edges, with a plurality of apertures 32 corresponding in number and in spacing to the apertures 29, such apertures 10 receiving pins 33 secured to each side of the end gate 27 adjacent its lower portion.

When it is desired to remove the mold the turn-buckles 18 are turned so as to draw the end members 16 of the rods 6 and 7 toward 15 each other and cause such rods to pivot about the lower opening 13 formed in the tubes 10 and 11. This pivoting action of the rods causes the side walls of the mold to diverge, that is to say, the lower portion of the 20 mold flares or moves outwardly away from the concrete wall. The latch members 30 are then disengaged from the pins 33 and the end member 27 is swung upwardly about the bolts 28. Inasmuch as the core 21 and 25 the auxiliary core 22 are both tapered downwardly they are readily withdrawn with the rest of the mold.

When it is desired to produce a straight portion of a wall, the expandible or telescopic end gate, Fig. 4, may be employed. The end member 27 is then removed by 30 removing the bolts 28, and the latch members 30 are turned upwardly about the pivot points 31 so that such latch members are out 35 of the way. The end gate, Fig. 4, comprises two similar members 34 and 35 which consist of right angle plates with the end portions overlapping. Between the side walls 36 and 37, bowed springs 38 are adapted to 40 be positioned in such a manner that the shoulders 39 of the springs, bear against such walls and tend to cause such end gate to expand. The projecting portions 40 of 45 these springs pass into openings 41 formed in the side members 1 and 2.

I claim:

1. A mold for concrete work, comprising side walls; means for holding said side walls in spaced relation, an end gate comprising 50 a pair of members having overlapping end portions and rearwardly extending flanges pivotally connected at their upper corners with the upper corners of said side walls, and a latch for temporarily holding the 55 lower portion of said gate in position.

2. A mold for concrete work, comprising side walls, means for adjustably spacing 60 said side walls, and an end gate composed of two relatively movable spring pressed members arranged to fit between said side walls and close one end thereof.

3. A mold for concrete work, comprising side walls, means for adjustably joining said side walls and an end gate for fitting between 65 said side walls at one end thereof, said

end gate comprising two relatively movable members and springs for forcing said members into engagement with the respective side walls, said springs forming securing means for fastening said members to said 70 side walls.

4. A mold for forming corners in hollow concrete walls, comprising a pair of side walls; a core positioned between said side walls; means for adjustably holding said 75 side walls and core in spaced relation; and an auxiliary telescopic core having means for locking engagement with said main core and one of said side walls, and an internally positioned spring for forcing the bottom portion of said auxiliary core into engagement with said main core and a side wall.

5. A mold for forming corners in hollow concrete walls, comprising a pair of side walls, a main core, means for holding said 85 side walls and core in spaced relation, and an expansible auxiliary core adapted to be detachably fastened in position between said main core and one of said side walls.

6. A mold for concrete work, comprising 90 side walls, upright bars secured to said side walls, and extending beyond the upper edges of said side walls, a longitudinally adjustable member spanning said mold and pivotally engaging said bars, and a turnbuckle 95 positioned above said member and loosely threadably engaging said bars, whereby when said turnbuckle is manipulated the relative angular position of said side walls may be adjusted.

7. A mold for concrete work, comprising a pair of side walls; a bar secured to each of said walls; a pair of telescopically associated members spanning said mold, each member directly and pivotally engaging one 105 of said bars adjacent the outer end of said member immediately above the corresponding side wall; and manual means for causing said bars to rock about their pivotal points of engagement with said telescopic 110 members to cause said side walls to diverge.

8. A mold for concrete work comprising side walls, bars fastened to said side walls and extending upwardly beyond their upper edges, a tubular member spanning said mold 115 and provided with openings adjacent each end through which said bars are arranged to pass, the openings through the lower side having a relatively snug fit with said bars, and the openings through the upper side 120 having a relatively loose fit with said bars, and means for adjusting the distance between the upper ends of said bars whereby said bars pivot adjacent the lower openings.

In testimony whereof I affix my signature 125 in the presence of two witnesses.

ARTHUR S. GREENE.
